UNITED STATES PATENT OFFICE.

EDWIN W. RICE, JR., OF SCHENECTADY, NEW YORK, ASSIGNOR TO GENERAL ELECTRIC COMPANY, A CORPORATION OF NEW YORK.

ELECTRIC ARC-LAMP.

SPECIFICATION forming part of Letters Patent No. 727,690, dated May 12, 1903.

Application filed August 26, 1901. Serial No. 73,214. (No model.)

To all whom it may concern:

Be it known that I, EDWIN W. RICE, Jr., a citizen of the United States, residing at Schenectady, in the county of Schenectady, State of New York, have invented certain new and useful Improvements in Arc-Lamps, (Case No. 1,724,) of which the following is a specification.

The object of this invention is to provide an arc-lamp for use on constant-potential circuits in which a longer arc may be maintained than with lamps as ordinarily constructed and a greater voltage drop across the arc with currents of small amperage, by which a wider zone of illumination is maintained and a smaller than common amount of steadyng resistance required.

In modern inclosed-arc lamps a potential drop of from seventy-five to eighty volts across the arc on circuits of one hundred and ten volts is maintained, it being found necessary with the regulating mechanism commonly employed to insert an idle resistance in the arc-circuit to prevent rupture of the arc. This is particularly the case with lamps operating under moderate currents, since the fluctuations in current strength, due to irregularities in the texture of the carbons, causes the arc to go out frequently unless such a steadyng resistance be employed.

It is the object of my invention to construct the lamp so that it may be employed with a small resistance in circuit and that a longer arc may be maintained with satisfactory illumination.

The chief difficulty with arc-lamp mechanism as heretofore constructed is that the regulating mechanism is not sufficiently rapid in action to keep the arc burning. There is great inertia of the moving parts, both mechanical and magnetic, which prevents a sufficiently prompt response of the core to the fluctuating current conditions. The decline of current on a hard spot in the carbon being encountered by the arc is instantaneous, and before the regulating device can permit the approach of the carbons to compensate for the increased resistance of the arc-stream the arc has been stretched to the snapping-point and extinguished, whereupon the carbons fall into contact and the arc must be

struck afresh. With an increase of voltage at the arc the arc-stream becomes more attenuated and is consequently more difficult to maintain unless a considerable steadyng resistance is employed. I provide for a quicker response of the regulating mechanism by using a short circuit for the regulating-coil containing a variable resistance which is automatically adjusted to suit the current flowing through the lamp. For this purpose I prefer to employ a shunt-circuit including a carbon contact or contacts the resistance of which is varied by a coil carrying the lamp-current, and the latter is rendered extremely sensitive by providing it with a very short magnetic circuit of laminated structure by which changes of magnetic density are rendered more rapid. Thus on a weakening current the tendency of the regulating-coil to hang fire or act sluggish is corrected by an instantaneous increase of carrying capacity of the shunt, which diverts current from the regulating-magnet, and therefore instantly weakens it and permits the carbons to approach. The controlling-coil for the resistance need not necessarily carry the entire lamp-current, but may be in shunt to the arc, or it may even be the regulating-coil itself, as will be hereinafter more fully described.

In the accompanying drawings, which illustrate the invention, Figures 1, 2, and 3 are diagrams of several types of lamp by which my improvements may be carried out.

In Fig. 1 is shown an arrangement in which the regulating-coil 1 is shunted by a circuit including carbon contacts 2 and 2^a and, if desired, a small auxiliary resistance 3, the contacts being normally held together by a stiff spring 4, but adapted to be separated and have the force of contact graduated by a magnet 5 in series with the lamp. This magnet should be provided with a short core, so as to have a short time constant, or, in other words, be very quick in magnetization and demagnetization, and is preferably given a long air-gap with the same end in view and is also laminated to prevent the development of eddy-currents and retardation of demagnetization. A dash-pot 6, resisting upward movement, is connected to the armature. The armature and connected parts are made as light

as possible to reduce inertia. A resistance 7, sufficient to absorb a drop of about fifteen volts, is employed, 8 representing the tripping-floor of the clutch. With a lamp as thus 15 organized any variation in the conductivity of the arc-stream is accompanied by a corresponding variation in the pull of the magnet 5. Its armature being within grip of its field at all times is instantly responsive and weakens or increases the contact in the shunt, thereby varying the resistance of the shunt-path. For an increase of current this action is not so material; but for a decrease it is 20 very important, since by reason of the construction of the magnet 5 it is much quicker to respond to a diminution of current than the regulating-coil 1, which has large magnetic and mechanical inertia; but when the shunt is lowered in resistance a largely-increased part of the lamp-current is diverted 25 from the coil 1, thereby greatly decreasing its power and permitting instant release of its core. Instead of placing the coil 5 in series with the lamp-current it may be placed in 30 shunt to the arc, as indicated in Fig. 2, the parts being so arranged that on an increase of voltage across the arc the resistance of the shunt will be decreased. The effect is here 35 the same in character as that in Fig. 1—namely, with an increase of current, which means a decrease in the thickness of the arc-stream and a consequent increase of arc-potential, more current flows in the controlling-magnet 5, thereby increasing the conductivity 40 of the shunt and causing a quicker release by the regulating-magnet 1 on its core.

The arrangement in Fig. 3 is substantially the same, except that here in place of a separate controlling-magnet the regulating-coil 40 itself may be employed for this purpose, a short laminated core 5^a being inserted in one end to act upon the resistance-varying armature. The carbon contacts are so placed that upon a decrease of current the armature 45 is retracted and the conductivity of the shunt increased.

Having thus described my invention, what I claim as new, and desire to secure by Letters Patent of the United States, is—

50 1. An arc-lamp having a by-pass around the regulating-coil, and a magnet of shorter time constant than said regulating-coil re-

sponsive to the lamp-current to control the same.

2. An arc-lamp having a variable resistance in a by-pass around the regulating-coil, and a magnet of shorter time constant than said regulating-coil governed by the arc to divert more current through the by-pass as the arc lengthens. 55

3. An arc-lamp having a variable resistance in a by-pass around the regulating-magnet, and a magnet of shorter time constant than said regulating-magnet responsive to the lamp-current and governing the resistance. 60

4. An arc-lamp having a variable contact in a by-pass around the regulating-magnet, an armature governing the contact, a stiff spring on the armature, and a magnet of shorter time constant than the regulating-magnet controlling the armature. 70

5. An arc-lamp having a shunt around its regulating-coil, a magnet of shorter time constant than the regulating-coil governed by the lamp-current, an armature controlled thereby for varying the resistance of the shunt, and a dash-pot to steady the movement of the armature. 75

6. An arc-lamp having a shunt around its regulating-magnet, a magnet of shorter time constant than the regulating-magnet governed by the lamp-current, an armature controlled thereby, and a variable contact carried by said armature for decreasing the resistance of the shunt with decrease of lamp-current, the armature and its attached parts being of small inertia to permit quick action. 80

7. An arc-lamp provided with a regulating-magnet, an auxiliary circuit for varying its magnetization, and a control-magnet to graduate the resistance of said auxiliary circuit, said control-magnet having a low time constant relatively to the regulating-magnet 90 and provided with an armature biased by a stiff retractile spring. 95

In witness whereof I have hereunto set my hand this 21st day of August, 1901.
